COUNTER STOOL BACK

Emanuel Lars Cederquist, Los Angeles, Calif.

Application March 5, 1938, Serial No. 194,090

1 Claim. (Cl. 155—164)

This invention relates to improvements in counter stools such as are installed before soda fountains, cocktail bars, and the like, and particularly to the construction of the back of the stool and its attachment to the seat of the stool.

The seats for stools of this character are generally mounted for rotation on suitable posts or pedestals, which posts or pedestals are attached by screws or the like to the floor. The seats in turn are generally supported on tripods and are attached thereto by suitable screws. It has generally been experienced that where the stool is equipped with a back rigidly attached to the back of the seat that customers leaning on the back or seating themselves heavily against the back bring about a loosening of the stool. This loosening may take place at the bottom of the pedestal, that is the screws which attach the pedestal to the floor may be loosened or stripped out of the screw holes. If the pedestal is rigidly anchored with screws of sufficient size to prevent their loosening, there is danger of the seat being loosened from the tripod that mounts it on top of the pedestal. Also, there is danger of the back being loosened where it is attached to the back of the seat.

It is an object of the present invention to provide a stool construction wherein the back is yieldably attached to the seat in such a manner that when severe stresses are imposed upon the back it may yield slightly and thus prevent loosening of the seat from the tripod or loosening of the pedestal from the floor.

Another object of the invention is to provide a means for attaching the back of a counter stool to its seat which is very simple and durable and which will maintain the back in tight engagement with the back of the seat of the stool.

With the foregoing and other objects in view, which will be made manifest in the following detailed description and specifically pointed out in the appended claim, reference is had to the accompanying drawing for an illustrative embodiment of the invention, wherein:

Figure 1 is a view in vertical section through the improved counter stool embodying my invention;

Fig. 2 is a rear view in elevation of the same;

Fig. 3 is a horizontal section taken through the frame of the seat of the stool illustrating the invention as applied to a seat having a curved back; and

Fig. 4 is a view similar to Figure 3, illustrating the invention as applied to a seat having a straight back.

Referring to the accompanying drawing wherein similar reference characters designate similar parts throughout, the counter stool is illustrated as being supported upon a post or pedestal 10 which is anchored to the floor such as by screws 11. On top of the post or pedestal there is disposed a tripod 12 having a post 13 extending into the top of the pedestal and enabling the tripod to rotate with respect thereto. The seat of the stool is supported on a suitable frame having side rails 14 and 15, a front rail 16, and a back rail 17. If the stool has a curved or rounded back the rear face of the back rail 17 is given a rounded convex shape in conformity therewith.

The bottom of the seat indicated at 18, is supported on this frame and may or may not be upholstered as indicated at 19. The tripod 12 is attached to the seat bottom such as by screws 20.

The back for the stool may be of any preferred construction and is illustrated as comprising a back member 21 which may or may not be upholstered as indicated at 22. To yieldably mount the back on the back of the seat and yet retain it in firm engagement therewith, forwardly tapering holes are bored in the rear rail 17 for the reception of the attaching bolts 23 which extend through the bottom of the back member and through the back rail. The heads of these bolts which may be positioned against the rear side of the back may be covered with the upholstery covering. Against the inner or forward face of the rail 17 there are positioned rubber washers 24 and against these rubber washers are placed small metal plates or washers 25. Nuts 26 are threaded onto the bolts against lock washers 27.

By this construction the back for the stool is firmly held against the back of the seat. At the same time however, due to the fact that the rubber washers 24 are formed of live rubber and consequently, are slightly compressible when severe stresses are placed on the back, the rubber washers give slightly under compression and thus the back may yield slightly. This relieves the stresses to some extent on screws 11 and 20 and at all events, due to the fact that the back is not rigidly connected to the seat, I have found from experience that loosening of screws 11 and 20 is completely eliminated.

When the seat of the stool has a rounded back as shown on Fig. 3, the bolts are preferably arranged on converging axes. The clearance afforded by the tapered holes in back rail 17 accommodates the necessary movement of these

bolts in the rail when severe stresses are applied to the back. When the back is straight as shown in Fig. 4, the axes of the bolts may be parallel extending through the tapered holes formed in the back rail.

Various changes may be made in the details of construction without departing from the spirit or scope of the invention as defined by the appended claim.

10 I claim:

A counter stool or the like comprising means providing a seat for the stool, said seat having

a frame including a back rail, means providing a back for the stool, means yieldably connecting the back against the back of the seat of the stool comprising bolts extending through the back and through the back rail of the frame of the seat, rubber washers on the bolts disposed adjacent the seat frame, metal washers thereover and nuts tightening the metal washers against the rubber washers, the holes in the back rail of the seat frame through which the bolts extend being forwardly tapered.

E. L. CEDERQUIST.
